Des. 204,511

Patented Apr. 19, 1966

204,511

DISPENSING CLOSURE

Walter Leeds and Lewis A. Micallef, New York, N.Y.,
assignors to Leeds and Micallef, New York, N.Y., a
partnership

Filed Jan. 25, 1965, Ser. No. 83,572

Term of patent 14 years

(Cl. D58—26)

FIG. 1

FIG. 2

FIG. 3

FIG. 4

FIG. 5

FIGURE 1 is a side elevational view of a dispensing closure showing our new design.

FIGURE 2 is a front elevational view thereof;

FIGURE 3 is a rear elevational view thereof;

FIGURE 4 is a top plan view thereof; and

FIGURE 5 is a top plan view thereof with one of the parts in a different position.

The dominant features of our design reside in the portions shown in full lines.

We claim:

The ornamental design for a dispensing closure, substantially as shown and described.
